CASTING APPARATUS

George M. Colburn, Greensburg, Pa.

Application February 9, 1942, Serial No. 430,137

5 Claims. (Cl. 22—57.3)

The continuous production of cast metal shapes directly from molten metal has received much attention in connection with such production of shapes in substantially finished form directly from molten metal.

This conception as applied to the continuous casting of heavy metals is by no means new. But it has been found to be necessary, in practice, to revise completely the teachings of the prior art in order to attain even experimental operativeness. However, in recent years the conception of direct and continuous production of cast metal shapes directly from molten metal has been reduced to commercial practice with respect to non-ferrous metals and alloys, but only after prolonged and intensive research.

In connection with ferrous metals, however, but little recent work has been done in connection with the continuous production of ferrous metal shapes.

This field is open to a great amount of experimental and development work; and the present invention lies in that field, the invention providing improvements in the art of continuous casting of metal shapes, particularly ferrous metal shapes, wherein the shapes are produced directly and continuously from the molten ferrous stock.

As has been indicated above, the conception of continuously casting metal shapes directly from molten metal is by no means new. The process of continuous casting comprises, generally speaking, flowing a continuous stream of metal to be cast into a suitable mold which usually is provided with some kind of a chilling device for quickly solidifying the metal in the mold, the solidified metal being withdrawn continuously from the mold as solidification of the new metal proceeds continuously, the rate of supply of molten metal into the mold being equal to the rate of withdrawal of the solidified casting.

The equipment for the commercial operation of continuous casting developments comprises, generally speaking, a continuous source of molten metal, which usually is a furnace which is adapted to hold a reservoir of molten metal of requisite degree of purity, from which reservoir a continuous supply of metal is allowed to flow quietly to a chilled mold, through which mold passes longitudinally a bore which is of the diameter of the casting to be produced, and which is the shape of the desired casting. This bore extends completely through the mold longitudinally thereof, and forms the mold cavity, it being plugged at one end with a bar of the metal that is being cast.

As molten metal flows into the mold it contacts the inserted end of the bar, and welds thereto as it freezes. Consequently, as the starting bar is withdrawn, this newly solidified, welded metal is withdrawn with it, the speed of withdrawal being proportioned to the cooling speed so as to enable fresh molten metal to weld onto the previously solidified metal and thus continuously solidifying permits the continuous withdrawing of a casting of indeterminate length.

Continuous casting has a double advantage in the rapid and economical production of metal shapes, and the soundness of the cast metal, which is entirely free from pores, pits, blowholes, pipes, and other unsoundness, the process producing metal of highest density.

One object of the present invention is to provide a method and apparatus whereby at least comparatively finished ferrous shapes (for instance steel rails, beams, or the like, by way of examples) may be produced directly and continuously from molten metal in a simple manner.

In general, the present invention comprises a plurality of sectional molds, the molds being divided into half-sections longitudinally, which half-sections become separately united to form a cavity corresponding in shape to the casting to be made, the sections being separable by mechanical means to release the solidified casting as the molds travel to a predetermined station on the conveyor system. A plurality of such sectional molds is provided, the molds being continuously assembled together adjacent to a metal pouring station so as to define a long, continuous mold made up of a plurality of sectional segments into which is poured and solidified the metal being cast.

The mold parts are moving continuously on the conveyor system, the segments and sections becoming separated at the releasing station for the casting, the resulting separated sections moving oppositely in a closed circuit, the spacing being such that as the molds are separated at the releasing station a corresponding number of sections are assembled and the resulting segments are aligned in engagement with each other, adjacent to the pouring station, the effect being that of a continuous mold of indefinite length. Suitably positioned cooling means are provided to facilitate the chilling of the metal in the mold, the casting obviously taking the shape of the mold cavity which the metal fills as it solidifies.

The solidified casting which forms continuously and of indefinite length may be given a

suitable surface finishing treatment as the casting is released progressively from the molds.

As mentioned above, suitable cooling means are provided in addition to only surface cooling by radiation, so that the molten metal is solidified completely before it leaves the molds. The metal is molten as it enters the mold assembly, and it is solid by the time it is released from the mold, the length of the casting thereby becoming increased continuously so long as molten metal is supplied to the molds.

As it leaves the molds, the continuous shape may be subjected to a rolling or other treatment which will be determined by the use for which the casting is intended.

Each mold section is recessed complementarily so that the mold assembly will produce a uniform cavity which extends unbrokenly through the assembled molds, and, in conjunction with a continuous conveyor or the like, comprising a plurality of segments adapted to engage the successive mold parts to form a top therefor, the cavity is of a shape which will impart to the casting, at least roughly, in desired final shape, which shape may be dressed, readily into final condition by a suitable treatment in means which are mounted in alignment with the moving casting as it is released from the molds.

The invention will be understood more readily by referring to the accompanying drawings, wherein,

Fig. 1 represents a plan view partly broken away of one form of an apparatus embodying the features of the present invention, parts being omitted for clarity and to eliminate confusion;

Fig. 2 is a side elevation of the apparatus of Fig. 1, parts being broken away;

Fig. 3 is a sectional elevation taken on the line III—III of Fig. 2 looking in the direction of the arrows;

Fig. 4 is a sectional elevation taken on the line IV—IV of Fig. 1, looking in the direction of the arrows;

Figs. 5, 6 and 7 are schematic sectional elevations through the mold and cooling means, these views indicating a variety of shapes that may be cast by the present equipment.

It will be understood of course that the illustrated form of apparatus for carrying out the invention is intended to be by way of illustration or example only as the specific details of construction obviously may be modified widely without departing from the scope of the invention, as may become suitable for any given installation of the equipment, so that it is intended and desired to embrace within the scope of this invention such modifications and changes as may be necessary to adapt the equipment to varying conditions and uses.

Referring more particularly to the drawing, A represents a conveyor system comprising two generally elliptical conveyor tracks, B and C, which merge together into a common side E. The conveyor system is inclined on a suitable mounting frame work F, the split molds being indicated by the complementary sections 9, 9' which are shown on opposite sides of the conveyor system, the sections traveling upwardly along the power-driven belts 10 and 12 and to be merged by the action of the conveyor tracks and assembled thereby on the common side E of the conveyor, which obviously slopes downwardly thus facilitating, by gravity, the downward travel of the molds to a separating wedge 11, details of which will be described hereinafter.

It will be apparent that, as mold sections 9 and 9' are assembled into segments by the tracks B and C, the assembling of succeeding mold segments will push the first segment along the side E, this action being repeated consecutively and continuously as the equipment operates, there being maintained continuously at loading station 13, a mold of constant length and cooling area; therefore, as each mold segment is separated and split by the wedge 11, a corresponding segment at the assembling station of the conveyor is assembled and made a part of the mold.

The common side portion E slopes downwardly 15 from the loading or charging station 13 and after the mold sections are separated by the wedge 11, which wedge guides the separated sections onto the belts 10 and 12 by way of the conveyor sections 15 and 17. These sections connect the lower end of the side E to the lower end of the belts 10 and 12, respectively, the mold sections passing from the side E onto the sections 15, 17, thence by gravity onto the lower ends of the belts 10 and 12, which pick them up and deliver them to downwardly inclined conveyor sections 18, 17', which connect the upper end of the belts 10 and 12 to the upper end of the common side E.

The sections 15, 17, 15' and 17' comprise rollers 30 19 which freely convey the mold sections to their respective stations.

Conveyor belts 10 and 12 are endless belts and are power-driven, thus moving the mold sections upwardly from the bottom to the top of the inclined framework F. The driving mechanisms are indicated generally at G, and need no detailed explanation, they being all similar and comprising a motor 20, speed reducer 21, driving pinion 23, gear 25, shaft 27 carrying a 20 sprocket 28 for driving a sprocket 30 at the foot of the conveyor belt, and a sprocket 31 for driving the conveyor chain 33. The sprocket 30 is driven by conveyor chain 33, and turns a shaft 35 on which is mounted another sprocket 37, similar to sprocket 30 and also driven by the conveyor chain 33.

This driving mechanism is duplicated on both sides of the conveyor system, as are all of the structural features of the conveyor system.

Additionally, adjacent to the charging station 13 and adapted to engage lugs 39 on the molds sections as these sections are assembled for pouring, there are positioned two large gears 41 and 41' which push the mold segments down the incline of the side E as the segments are filled successively with molten metal. These gears are duplicated on both sides of the section E and are driven similarly by a motor such as that indicated at 43, which operates through a speed reducer 45, the motor shaft having a bevel pinion 49 thereon, which in turn drives a bevel gear 51 on the bottom end of an inclined shaft 53, at the top end of which there is mounted the gear 41.

Positioned beneath the common section E is a cooling jacket or other cooling means 55 for chilling the metal in the mold. A suitable cooling fluid, such as water, is circulated therethrough.

The mold segments, as these are assembled and brought end to end, receive molten metal from any suitable source which is represented schematically by a ladle 56 which is illustrated as pouring molten metal 57 into a refractory charging funnel 58 which opens into the cavity of the

mold. The gears 41, 41' advance the molds, the metal therein being quickly cooled below its melting point; but the declivity of the molds on the part E facilitates the complete filling thereof through the gravitational flow of metal in the molds.

As the mold is advanced, the shape is completed by the segments 59 of a vertical conveyor which rotates in the direction of the movement of the mold, the segments 59 making a top for each of the mold segments and further molding the still plastic metal into at least approximately the final shape which is desired, whether that be a billet or a slab, or a rail, or any other desired shape.

The segments 59 are carried on an endless chain 61, which chain passes over sprocket wheels 63, 65, the latter being driven by a drive belt 67 which in turn is driven by a motor 69.

As the mold with the solidified portion of the casting is progressed towards the downward end of the conveyor system, the leading segments of the mold progressively contact the wedge 11, which is mounted to engage the mold segments. Each section of the mold segment is provided with an upstanding flange 71, 71' which engage the sides of the wedge 11 and separate the sections, the flanges causing the mold sections to be guided onto the respective sides of the conveyor.

The wedge 11 is mounted as follows:

Suitable supporting standards, indicated at 13, 13' are disposed adjacent to the lower portion of the conveyors, as will be apparent from the drawings, these being joined at their tops by an I-beam 75, which carries the wedge 11, this being a substantially triangular plate which is welded or otherwise mounted on a vertical tapering web 77, which in turn may be welded to a plate 79 which is secured suitably to the beam 75; or, the parts 11, 77, and 79 may be an integral casting.

The wedge 11 is mounted so that its point is directed against the approaching filled molds, its apex meeting the juncture between the mold sections, so that the sections of molds separate and ride along the sides of the wedge which engage the ribs 71, 71' along the tops of the mold section, thereby separating the sections and releasing the casting 83, while guiding the sections onto the complementary conveyors. It will be seen that the wedge 11 extends over the roll conveyors 15 and 17 to enable the sides of the wedge to guide the mold sections well onto both conveyors so that each section will be placed properly on the rolls 19 of the roll conveyors for reassembly.

As the casting 83 is freed by the action of the wages, it may pass to a run-out table 85, rollers of which are indicated at 87, these rollers being driven suitably, such as through a sprocket wheel 89. The casting may pass thence through finishing means, such as a stand of finishing rolls 91, and thence to sawing instrumentalities (not shown) which preferably are designed to saw the casting into predetermined lengths without interrupting the continuous movement of the casting.

While the casting 83 shown in the drawings is specifically a rail, any other shape may be cast quite readily in accordance with the particular shape of the mold cavity as defined by the complementary mold sections.

Thus, in Fig. 5, the mold sections 9 and 9' define a shallow rectilinear cavity, the top of

which is closed by conveyor segment 59, to produce a rectilinear slab casting 83.

In Fig. 6, the cavity formed between the mold sections 9 and 9' is deeper than is the mold cavity of Fig. 5, the cavity of Fig. 6 producing, as shown, a rectilinear billet casting 95.

In Fig. 7, the cavity formed between the sections 9 and 9' corresponds in shape to the particular shape to be cast, which is shown as being an I-shaped casting, such as an I-beam 97.

The molds are made of suitable material, such as cast iron, from which the casting shrinks as the steel solidifies.

The funnel 58 may be any suitable refractory device, properly insulated to hold heat, such as with fire-brick or the like, and it may, likewise, be heated externally if necessary. This funnel 58 provides a reservoir of molten metal to supply the metal continuously to the molds between pourings from ladle 56, and, additionally, it breaks the head of metal resulting from the elevation at which the ladles are poured.

I claim:

1. Apparatus for the continuous casting of metal shapes, which comprises, in combination, 25 a supply of molten metal, a plurality of separate molds each of which consists of separate complementary sections, which when assembled define a mold cavity for receiving molten metal, mechanism for aligning the molds together at the supply of molten metal so that the cavities of the said molds are in communication with each other for receiving molten metal from the source and defining a continuous elongated channel of desired shape, means for continuously moving the molds in metal-receiving position, cover means for the said molds, mechanism for covering the molds, instrumentalities for continuously applying the cover means adapted to engage the successive molds as the molds move thereagainst, the said means being mounted for engaging the molds between the complementary sections, thereby forcing the sections apart and to the molds, and means for releasing the solidified casting from the molds.

2. Apparatus for the continuous casting of metal shapes, comprising, in combination, a pair of endless conveyor courses including a stationary runway common to the two courses, each course comprising a power-driven section extending substantially parallel to the stationary runway, an additional section at each end of the power-driven section connecting the power-driven section to the stationary runway, the conveyor courses having converging portions at one end extending to the stationary runway and diverging portions at their opposite ends, complementary mold sections on the conveyor courses which assemble the mold sections into an uninterrupted mold on the stationary runway, means for moving the assembled mold along the runway, means for supplying molten metal to the assembled mold as it moves along the runway, chilling means for cooling the mold to solidify the casting, and instrumentalities for releasing the solidified casting from the mold.

3. An apparatus for the continuous casting of metal shapes, which comprises, in combination, an endless conveyor bed including oppositely moving conveyor instrumentalities and a stationary section common thereto, a continuous mold composed of individual segments imparting flexibility to the mold, the said segments being composed of complementary separable sec-

tions defining a continuous mold cavity as the mold is assembled, means adjacent to the stationary sections for continuously supplying molten metal to the mold, power-driven means for continuously moving the mold along the stationary sections, and a rigidly mounted separating wedge for separating the said mold sections and guiding the separated sections onto the oppositely moving conveyor instrumentalities.

4. Apparatus for the continuous casting of metal shapes, which comprises, in combination, an endless conveyor bed including oppositely moving conveyor instrumentalities and a stationary section common thereto and communicating with the moving conveyor instrumentalities, a continuous mold composed of individual independent segments, each segment being composed of complementary separable sections defining a continuous mold cavity when the said sections and segments are assembled at the stationary section of the conveyor bed, means adjacent to this stationary section for continuously supplying molten metal to the assembled mold instrumentalities for covering each segment of the mold as it is filled, and for pushing the assembled segments along the said stationary conveyor bed section as they are filled, chilling means for the mold to solidify quickly the molten metal supplied thereto, and separating means for engaging successive mold segments for separating them and for separating the complementary sections of each mold, thereby re-

leasing the casting, the separating means defining a guide for the separated sections for guiding them onto the oppositely moving conveyor instrumentalities.

5. Apparatus for the continuous casting of metal shapes, which comprises, in combination, an endless conveyor bed, including oppositely moving conveyor instrumentalities and a stationary section common thereto and communicating with the moving conveyor instrumentalities, a mold composed of independent segments, each segment being composed of separable sections defining a continuous mold cavity when the said sections and segments are assembled at the stationary section of the conveyor bed, means adjacent to this stationary section for continuously supplying molten metal to the mold as it is assembled at the said stationary section of the conveyor, instrumentalities for covering each segment of the mold as it is filled and for pushing the mold along the said stationary bed section, and separating means for engaging successive mold segments for separating them and for separating the complementary sections of each segment while guiding the resulting separated segments onto the oppositely moving conveyor instrumentalities which are adapted to reassemble the said sections and segments into the mold at the said stationary section, before previously assembled parts are filled with metal, thereby making a continuous mold.

GEORGE M. COLBURN.
